QUICKLY RELEASEABLE MOUNTING MEANS
FOR LAMP SHADES

Bertram W. White, Winnipeg, Manitoba, Canada

Application June 23, 1947, Serial No. 756,403

3 Claims. (Cl. 240—128)

1

This invention relates to new and useful improvements and structural refinements in lamp shade structures, more specifically, structures such as are commonly employed in association with ceiling lamps, and the principal object of the invention is to provide a structure of the character herein described, in which the lamp shade may be quickly, easily and conveniently applied or removed.

In lamp shade structures of conventional design, the lamp shade surrounding the incandescent lamp is usually retained in position by means of three or more screws provided on the base on which the incandescent lamp is mounted. Therefore, in order to remove or to install the lamp shade, it is necessary to loosen or tighten the retaining screws, as the case may be.

It is, therefore, a further object of the invention to simplify the removal and installation of the lamp shade, as aforesaid, by providing only to a plurality of simultaneously actuated keepers one locking knob which is operatively connected for retaining the lamp shade in position.

Another object of the invention is to provide a lamp shade structure which is simple in construction and operation, which will not easily become damaged, and which will readily lend itself to economical manufacture.

An additional object of the invention is to provide a lamp shade structure which is otherwise well adapted for the purpose for which it is intended.

With the above more important objects in view and such other objects as may become apparent as this specification proceeds, the invention consists essentially of the construction and arrangement of parts as shown in the accompanying drawings in which:

Fig. 1 is a perspective view of the invention;

Fig. 2 is a vertical cross sectional view thereof, with the lamp shade removed, the same being taken substantially in the plane of the line 2—2 in Fig. 3;

Fig. 3 is a cross sectional view, taken substantially in the plane of the line 3—3 in Fig. 2;

Fig. 4 is a fragmentary cross sectional view showing a portion of the lamp shade in the locked or secured position;

Fig. 5 is a cross sectional view, similar to that shown in Fig. 4, but illustrating the first step in the removal of the lamp shade;

Fig. 6 is a cross sectional view, similar to that shown in Figs. 4 and 5, but illustrating the second step in the removal of the lamp shade;

Fig. 7 is a cross sectional view, taken substantially in the plane of the line 7—7 in Fig. 5;

2

Fig. 8 is a perspective view of the locking knob shaft and bracket used in the invention;

Fig. 9 is a perspective view of one of the rods;

Fig. 10 is a perspective view of another of the rods;

Fig. 11 is a perspective view of another bracket used in the invention;

Fig. 12 is a perspective view of a still further bracket; and

Fig. 13 is a perspective view of one of the guides used in the invention.

Like characters of reference are employed to designate like parts in the specification and throughout the several views.

Referring now to the accompanying drawings in detail, the invention consists of a lamp shade structure designated generally by the reference character 15, the same embodying in its construction a mounting base 16 which is adapted for attachment to the ceiling in any suitable manner and includes an annular wall 17 provided at the lower edge thereof with an annular extension 18 which, in turn, is formed with an inturned flange 19.

25 The inner edge of the flange 19 is upturned as at 20, and serves as a keeper for a downwardly extending, annular wall 21 provided on a lamp mounting plate 22. This plate is of a more-or-less conventional design, and is provided with a

30 suitable central opening 23 to receive the socket for the incandescent lamp (not shown) and with a plurality of keyhole apertures 24 to receive the bolts with which the flange of the lamp socket is secured in place. The structure of the lamp socket, flange and bulb assembly is, of course, of a conventional character and further description thereof at this point is deemed unnecessary.

35 A suitable lamp shade 25, formed at the mounting edge portion thereof with an annular groove 26 terminated by an out-turned lip 27 is receivable in the recess 28 defined by the annular wall 21, that is to say, the mounting edge portion of the shade is receivable in said recess, as is best shown in Figures 4 and 5.

40 The essence of novelty of the invention resides in the provision of the particular means for removably retaining the lamp shade in position, said means consisting of a plurality of equally spaced keepers 29, one end portion of which is adapted to project into the groove 26 and to engage the out-turned lip 27 of the lamp shade 25, as will be presently described.

45 The remaining end portions of the keepers 29 are equipped with counter-weights 30 and each of the keepers is pivoted medially of its length, as at 31, to a plate or block 32. A suitable spacer

33 is interposed between each of the keepers and each of the blocks, as will be clearly apparent.

Accordingly, each of the keepers together with the associated spacer and block may be referred to as a keeper assembly, and it will be noted that each keeper assembly is slidably positioned, that is to say, each of the blocks 32 is slidably positioned, in a guide 34, best shown in the accompanying Figure 13. Each of the guides assumes the form of a box-like channel which is formed on one side thereof with a longitudinal opening 35, and is also provided at one end thereof with a mounting flange 36. It will be observed that the flanges 36 of the guides 34 are secured as at 37 to the outer surface of the aforementioned wall 21, and that the keepers 29 project into the recess 28 through suitable slots 30' with which the wall 21 is provided.

It will be also noted that the blocks 32 are disposed adjacent the openings 35 of the guides 34, and each block is provided with a suitable aperture to receive an arm 38 of what may be referred to as a bell crank 39. These bell cranks are pivotally connected as at 40 to a plurality of brackets 41 which are, in turn, secured to the outer surface of the aforementioned wall 21 by suitable rivets 42. One of these brackets which has been designated by a distinguishing reference character 43 is similar to the brackets 41, but is provided with an additional flange 44, formed with an aperture 45, the purpose of which will be hereinafter more fully described.

With reference to the accompanying Figure 7, it will be apparent that by moving the cranks 39 in the direction of arrow 46, the keepers 29 will be retracted in the direction of the arrow 47 into the guides 34, and conversely, by moving the cranks in the relatively opposite direction, the keepers will be projected into the recess 28 through the slots 30'. The various cranks and keepers are adapted for simultaneous actuation, this being accomplished by connecting one crank to another by means of a synchronizing rod 48. Two of these rods are provided for connecting together the three cranks as illustrated in Figure 3, and it will be noted that the rods are provided at the ends thereof with suitable eyes 49 so that they may be secured to the cranks by the pivot pins or rivets 50. The rods are angulated substantially as shown, so that they clear the wall 21.

The particular crank which is pivoted to the aforementioned bracket 43 is operatively connected to a further rod 51 which is also attached to an angularly disposed eye 52 provided at one end of a locking knob shaft 53. This shaft is rotatably journaled in a bracket 54, configured substantially as shown, which is secured to the outer surface of the wall 21, as at 55, matters being so arranged that an end portion of the shaft 51 projects outwardly from the extension 18 and carries a suitable locking knob 56.

Accordingly, it will be seen that by rotating the knob 56, the rods 51, 48 will be moved in the direction of the arrows 57 and the dogs 29 will be retracted from the recess 28 into the guides 34. Means are provided for returning the knob 56 to its original position and also, the keepers 29 into their projected positions, said means consisting of a tension spring 58 which is anchored at one end to the eye 52 on the shaft 53, and at the other end, in the aperture 45 of the lug or flange 44.

Finally, it should be explained that the keepers 29 are provided in the lower edge portion thereof with notches 59 which are adapted to engage the

edge portions of the slots 30' in the annular wall 21 when the keepers are in their projected positions.

Having thus described the structure of the invention, its method of operation will now be explained.

With particular reference to the accompanying Figure 4, when the lamp shade 25 is in position, the out-turned lip 27 thereof engages and 10 bears upon the projecting portions of the keepers 29 so that the notches 59 engage the adjacent edges of the slots 30', in which manner the lamp shade is firmly and securely held in place.

When it is desired to remove the lamp shade 15 from the mounting base 16, it is only necessary to lift the shade upwardly (in the direction of the arrow 60), while, at the same time, the knob 56 is rotated. This operational step is illustrated in the accompanying Figure 5, and it will be noted that as soon as the lamp shade is raised, the counter-weights 30 associated with the 20 keepers 29 will "over-balance" the keepers, so that the notches 59 are disengaged from the edges of the slots 30'. Thereupon, by simply 25 turning the knob 56 as aforesaid, the several keepers will be retracted (by virtue of the cranks 39 and rods 48, 51) into the guides 34, so that the lamp shade 25 may be simply "dropped" or withdrawn from the recess 28 of the mounting 30 base, as indicated in the accompanying Figure 6.

Thereupon, the knob 56 may be released, and the spring 58 will return the keepers into their projected positions, as will be readily understood. When it is desired to reinstall the lamp shade, 35 the keepers are again retracted by turning the knob 56, so that the mounting edge portion of the lamp shade may be inserted in the recess 28, substantially as shown in Figure 5. The knob 56 is then released, thereby permitting the keepers 40 to engage the groove 26 of the lamp shade, whereupon by simply relaxing upward support of the lamp shade, the latter will be permitted to "drop" so that the lip 27 thereof bears upon the keepers and urges the notches 59 into their locked 45 position on the edges of the slots 30', as shown in Fig. 4.

It is believed that the advantages and use of the invention will be clearly apparent from the foregoing disclosure, and accordingly, further 50 description thereof at this point is deemed unnecessary.

While in the foregoing there has been shown and described the preferred embodiment of this invention it is to be understood that minor 55 changes in the details of construction, combination and arrangement of parts may be resorted to without departing from the spirit and scope of the invention as claimed.

Having thus described the invention what is 60 claimed as new is:

1. In a lamp shade structure, an annular mounting base, a shade having an outturned marginal lip, projectable and retractable keepers slidably in said base and in projected positions 65 supportably engaging said lip, manually actuated means for projecting and retracting said keepers, said keepers being formed with notches lockably engaging said base when said keepers are projected and supporting said shade, whereby said 70 manually actuated means are positively locked in a keeper projecting position and gravity actuated means for automatically disengaging said notches from said base in the absence of supportable engagement of said lip by said keepers.
2. The device as defined in claim 1 wherein said

keepers are slidable but pivotally mounted intermediate of their ends and include end portions engageable with said lip, said gravity actuated means comprising counterweight members provided at the remaining end portions of said keepers.

3. The device as defined in claim 1 wherein said base includes an annular wall formed with slots to slidably receive said keepers, said notches being lockably engageable with edge portions of said slots.

BERTRAM W. WHITE.
